ELECTRIC WEFT DETECTING SYSTEM FOR LOOMS

Victor F. Sepavich, Worcester, Mass., assignor to
 Crompton & Knowles Loom Works, Worcester,
 Mass., a corporation of Massachusetts

Application December 27, 1948, Serial No. 67,339

5 Claims. (Cl. 139—370)

1

This invention relates to electric weft detecting systems for looms and it is the general object of the invention to provide such a system with circuits which will energize the loom controlling electromagnetic device, such as a solenoid, for a short part only of the time elapsing between its energization and the time at which the loom uses the control exercised or indicated by the device.

Electric weft detecting systems for stopping looms generally employ some form of feeler or detector and a solenoid which positions one part of the loom, such as a knock-off mechanism, for operation by another part thereof. There is ordinarily an appreciable interval of time between indication of weft exhaustion by the weft detector and operation of this other part to effect a change in loom operation, such as loom stoppage. In electric weft detecting systems commonly used the solenoid is required to be energized throughout this entire period of time and because of this fact it has been necessary to use a solenoid large and expensive enough to withstand continued energization, even though a brief momentary energization is all that is required.

It is an important object of the present invention to provide an electric detecting system which includes a normally charged electric condenser for energization of the solenoid and means for discharging the condenser through the solenoid incident to indication of weft exhaustion. The solenoid is therefore energized for the brief interval of time only during which the condenser discharges.

A type of electric weft detector which has gone into general use employs a pair of detector fingers or prongs for engagement with a denuded metallic ferrule on the bobbin of a depleted weft shuttle. It has been found that these detector fingers are likely to rebound when they are struck by the metal ferrule so that the total amount of time during which the detecting circuit can be closed is materially less than that fraction of the cycle of the loom during which the fingers would contact the ferrule if there were no rebounding. The amount of electric power which would otherwise pass through the detecting circuit is therefore reduced to an amount insufficient to operate a relay or the like and also charge a condenser.

It is a still further object of the invention to employ a normally closed charging circuit for the condenser and a relay responsive to very small currents which when energized by momentary closure of the detector circuit will connect the condenser to a discharge circuit including the

2

solenoid and simultaneously open the charging circuit so that current from a primary source, such as a transformer, cannot flow through the solenoid.

5 With these and other objects in view which will appear as the description proceeds, the invention resides in the combination and arrangement of parts hereinafter described and set forth.

In the accompanying drawings, wherein a convenient embodiment of the invention is set forth,

Fig. 1 is a diagram of the electric circuits forming the subject matter of the present invention in their normal condition prior to indication of weft exhaustion, and

15 Fig. 2 is a view similar to Fig. 1 but showing the conditions which exist when the weft detector indicates weft exhaustion.

The invention is applicable to various types of electromagnetic loom control systems not necessarily limited to stopping mechanisms, but is shown herein as applied to such a mechanism for the purpose of stopping loom operation upon exhaustion of weft. The stopping of the loom may be effected by means shown, for instance, in prior

25 patents to Payne Nos. 1,873,465 and 2,266,474.

The knock-off mechanism employs a cam 10 which may be on the bottom or two pick shaft of the loom to rock an actuator lever 11 periodically during loom operation, usually at two-pick intervals. A knock-off or stopping lever 12 is normally in non-stopping position during loom operation and has attached thereto a link 13 which is ordinarily in the down or non-stopping position thereof due to the fact that a solenoid S is

35 normally deenergized and its core 14 is in low position. During normal running conditions the cam causes the lever 11 to have periodic working strokes to the left, but the link 13 will be

40 down out of the path of the lever so that the stopping lever 12 will remain unchanged. If the solenoid is energized its core 14 is lifted to raise the link to stopping position in the path of lever 11, whereupon the lever 12 is moved from non-stopping position to stopping or knock-off position to effect loom stoppage.

A weighted lock or holding detent 15 under link 13 is normally in the position shown in Fig. 1, but when the link is raised the detent moves to a vertical position to support the link in stopping position. When the link is moved to the left by lever 11 a notch 16 in the underside of the link moves over detent 15. When the link returns to the right the detent is returned to its normal non-supporting inclined position. For

further details of the detent reference may be had to the aforesaid Payne patents.

Detection of the condition of weft in the shuttle ordinarily occurs when the lay is at front center, but the cam 10 is usually set so that it will initiate loom stoppage later in the loom cycle and at a time which will permit complete loom stoppage before the next picking operation, which ordinarily occurs when the lay is at top center. There is therefore an appreciable interval of time lapsing between indication of weft exhaustion by the weft detector and movement of the link 13 by lever 11. In the past the solenoid S has been maintained energized throughout this interval and because of this fact it has been necessary to employ a solenoid which could withstand continued energization.

The weft detector D employs right and left detector fingers 17 and 18 for cooperation with the metallic ferrule 19 on bobbin B. The bobbin is presented to the detector by forward movement of the lay and when the ferrule is covered with weft the detector fingers 17 and 18 are insulated from each other; but when weft exhaustion occurs the ferrule is uncovered and electrically connects the fingers. These fingers are ordinarily maintained in their normal rearward position by springs (not shown) which yield as the fingers move forwardly.

When the metal ferrule strikes the fingers the latter are likely to rebound, each detector finger rebounding in a manner determined partly at least by its own spring. The rebounding of the detector fingers is likely to be unequal and one finger may return to contact with the ferrule and start a second rebound while the other finger due to its rebounding is still out of contact with the ferrule. Under these conditions no current can flow through the detector for the period at least during which the fingers 17 and 18 rebound and are not in simultaneous engagement with the ferrule. If the solenoid is directly energized by the detector circuit this rebounding may prevent its full energization and it is for this reason that a relay is employed which can be energized by a much smaller current than would be required by the solenoid, this relay being in the circuit of the detector and effective to establish contacts which control the circuits associated with the solenoid when the detector indicates weft exhaustion.

As shown for instance in Fig. 1, a transformer T supplying alternating electric current has leading therefrom line wires 20 and 21, the latter being electrically connected by wire 22 to the detector finger 18. Finger 17 is connected electrically by wire 23 to a contact 24 which normally engages a contact plate 25 on but insulated from the knock-off or stopping lever 12 when the latter is in its normal running or non-stopping position. A second contact 26 also engaging plate 25 is connected by wire 27 to a relay 28 connected by wire 29 to the other line wire 20. This constitutes a detecting circuit which is ordinarily open at the weft detector but will be closed by simultaneous engagement of the two detector fingers 17 and 18 with the ferrule 19, at which time the detecting circuit will be closed and the relay will be energized to effect closure of certain contacts and opening of other contacts associated with it.

Because of the briefness of closure of the detector circuit for reasons already described, particularly at high loom speeds, a holding circuit means is provided which bypasses or short circuits the weft detector. This circuit is as follows: line wire 20, wire 29, relay 28, wire 27, contact 26, 75

contact plate 25, contact 24, wire 30, contact 31, contact plate 32, (controlled by the relay), contact 33, wire 34, and wire 21 back to the transformer T. This holding circuit is maintained closed subsequent to the detecting period and after the ferrule 19 moves rearwardly away from the detector due to lay motion, and so long as lever 12 is in running position.

The solenoid is energized by a condenser C 10 which is normally connected across the lines 20 and 21 by the following charging circuit: wires 21 and 35; contact 36, contact plate 37 (controlled by the relay), contact 38, wire 39, rectifier 40, wire 41, condenser C, and wire 42 to the other line 15, wire 20. The plate 37 electrically connects the contacts 36 and 38 when the relay 28 is deenergized so that the condenser C is normally connected across the transformer and in a fully charged condition. When relay 28 is energized, 20 however, the plate 37 moves away from the contacts 36 and 38 and opens or interrupts the charging circuit.

The relay 28 also controls the following solenoid or condenser discharge circuit: condenser C, 25 wire 41, wire 45, solenoid S, wire 46, contact 47, contact plate 48 (controlled by the relay), contact 49, wire 50, and wire 42 back to the condenser. This circuit is normally open but when the relay 28 is energized to cause plate 48 to engage contacts 47 and 49, the discharge circuit is closed and the condenser discharges through the solenoid to energize it with resultant lifting of the link 13 to its stopping position. The discharge circuit is connected to the charging circuit 30 at a point between the rectifier and the condenser; but opening of the charging circuit by movement of plate 37 away from the contacts 36 and 38 prevents current from the transformer from passing to the solenoid or through the discharge circuit, and the solenoid will be energized only by such current as is derived from the condenser C. As soon as the latter is completely discharged the solenoid will become deenergized and the holding detent 15 will maintain the link 13 in raised position even though current has ceased to flow in the solenoid. The circuits will then be as indicated in Fig. 2.

At a later time in the loom cycle actuator lever 11 will move the link 13 to the left and rock knock-off lever 12 in a counter-clockwise direction to stopping position, one of the effects of which is to stop the loom and another effect of which is to move contact plate 25 away from contacts 24 and 26. This results in opening the holding circuit and causing deenergization of the relay 28. The contact plates 32, 37 and 48 thereupon return from their indicating position shown in Fig. 2 to their normal position indicated in Fig. 1.

60 From the foregoing it will be seen that the detector system provides a normally charged condenser and a normally open discharge circuit including a solenoid, together with means for closing the discharge circuit when the detector indicates weft exhaustion. The solenoid is associated with a part, such as link 13, which is moved to controlling or knock-off position when the solenoid is energized, and it is therefore not necessary to continue energization of the solenoid 65 beyond the time required to lift the link 13. The condenser and solenoid have such electric characteristics that the condenser is able to maintain the solenoid energized for several cycles of alternating current sufficiently long to perform its required work. The holding circuit will be opened 70

when the knock-off lever 12 moves to stopping position, whereupon the contacts controlled by the relay 28 return to their normal condition. While the switch including contacts 24 and 26 and the contact plate 25 has been shown herein as being opened by knock-off lever 12, it is apparent that the invention is not limited to a particular part for controlling the switch. If desired a break in one or the other of the main line wires 20 or 21 could be effected by the shipper mechanism when moving to stopping position, but this has not been illustrated, since it is well understood. It will further be seen that a very brief contact established by the weft detector and ferrule 19 will suffice to set the detector system into operation and that a considerable period of time can elapse between indication of weft exhaustion by the detector and the ultimate use which the loom makes of this indication, that use as specifically set forth herein being loom stoppage. The invention, however, is not to be limited to loom stoppage, since it will suffice if discharge of the normally charged condenser through the solenoid effects setting of some part of the loom to be followed by a change in loom 25 operation.

Having thus described the invention it will be seen that changes and modifications of the foregoing specific disclosure may be made without departing from the spirit and scope of the invention.

What is claimed as new is:

1. In an electric weft detecting system for a loom having a source of alternating current electric power, an electric weft detector and mechanism effective to cause a change in loom operation when a solenoid is energized, said system comprising a charging circuit including a condenser, a normally closed switch and a rectifier, a discharge circuit including the condenser, solenoid and a normally open switch connected to the charging circuit between the rectifier and condenser, and electric means effective upon indication of weft exhaustion by the weft detector to open said normally closed switch to prevent flow of electric current from said source through the rectifier to the solenoid and close said normally open switch to energize the solenoid by electric power derived from the condenser only.

2. In an electric weft detecting system for a loom having a source of electric power, an electric weft detector and mechanism effective to cause a change in loom operation when a solenoid is energized, said system comprising an electric detecting circuit including a normally de-energized relay effective upon indication of weft exhaustion by the detector to energize the relay, a holding electric circuit completed through the relay and source upon energization of the relay, a normally closed electric charging circuit including the source and a condenser, a discharge circuit normally open including the condenser and solenoid, electric means acting due to energization of the relay to open the charging circuit and close the discharge circuit to cause energization of the solenoid by electric power derived from the condenser, and means acting subsequent to energization of the solenoid effective to open the holding circuit, whereupon the relay becomes deenergized, the charging circuit is closed and the discharge circuit is opened.

3. In an electric weft detecting system for a loom having a source of electric power, an electric weft detector which can indicate weft exhaustion at a given point only in the loom cycle

and having mechanism effective at a later point in the loom cycle to cause a change in loom operation if a part thereof has previously been moved due to energization of a solenoid, the system comprising a normally open electric detector circuit powered by said source and including the detector and a relay and closed to energize the relay when the detector indicates weft exhaustion at said given point in the loom cycle, an electric charging circuit including an electric condenser normally closed to charge to condenser by power derived from said source, a normally open electric discharge circuit connected to the charging circuit and including the solenoid and condenser, and electric means effective upon energization of the relay to close the discharge circuit to energize the solenoid by power derived from the condenser and open the charging circuit prior to said later point in the loom cycle to the end that the solenoid will be energized by power derived from the condenser only and move said part and become deenergized prior to said later point in the loom cycle.

4. In an electric weft detecting system for a loom having a source of electric power, an electric weft detector and stopping mechanism normally in non-stopping position but moving to stop the loom incident to but subsequent to energization of a normally deenergized solenoid, the system comprising an electric detecting circuit powered by said source and including a relay and a switch normally closed when the stopping mechanism is in non-stopping position and closed to energize the relay when the weft detector indicates weft exhaustion, a normally open holding electric circuit powered by said source including said switch and relay and closed as a result of energization of the relay, a normally closed charging electric circuit including an electric condenser powered by said source to keep said condenser normally charged, means opening said charging circuit as a result of energization of the relay, and a normally open discharge electric circuit including the condenser and solenoid closed as a result of energization of the relay to energize the solenoid by the condenser only and independently of said source, movement of the stopping mechanism to stopping position due to energization of the solenoid opening said switch and holding circuit with resultant deenergization of the relay and closure of the charging circuit and opening of the discharge circuit.

5. In an electric weft detecting system for a loom having a source of electric power and an electric weft detector which is capable of indicating weft exhaustion, the loom having a periodically rocking actuator lever, a knock-off lever, and a link operatively connected to the knock-off lever normally out of operative position relatively to the actuator lever but moved into operative position with respect to the actuator lever when a solenoid is energized, a holding detent operative upon movement of the link to operative position with respect to the actuator lever to move to holding position to maintain said link in said operative position relative to the actuator lever, the system comprising a normally open electric detector circuit powered by said source and including the detector and a relay closed to energize the relay when the detector indicates weft exhaustion, an electric charging circuit including an electric condenser normally closed to charge the condenser by power derived from said source, a normally open electric discharge circuit connected to the charging circuit and in-

cluding the solenoid and condenser, and electric means effective upon energization of the relay to close the discharge circuit to energize the solenoid by power derived from the electric condenser a sufficient length of time to enable said holding detent to move to the holding position thereof relative to the link, said holding detent remaining in the holding position thereof subsequent to complete discharge of the condenser to maintain said link in the path of said actuator lever.
